[57] ABSTRACT

A storage and transfer hopper with interlocked outer and inner charging doors. The doors are prevented from opening at the same time by a locking mechanism which prevents rotation of the respective shafts to which the doors are connected. The locking mechanism is biased to keep the inner door closed normally. The hopper is used to feed a thermoplastic scrap granulator and interlocked doors permit reduction in the sound level from the granulator as well as prevent fly-back of the ground scrap.

HOPPER WITH INTERLOCKED CHARGING DOOR

BACKGROUND OF THE INVENTION

The present invention relates to storage and transfer hoppers, particularly for use with thermoplastic scrap granulators.

The production of thermoplastic articles results in the generation of substantial amounts of scrap thermoplastic material which is reground to permit its reuse. The scrap material is conventionally collected, conveyed and transferred to a hopper which is disposed over a conventional scrap granulator. It is desirable to reduce the noise level produced from such scrap handling systems. The feeding of thermoplastic scrap to the granulating chamber can result in scrap plastics being propelled back away from the high speed cutting blades of the granulator, and it is desirable that such particles be contained within the hopper and not permitted to fly out into the production area.

It is therefore desirable to provide a hopper which has interlocked charging doors whereby one door is always closed even during charging of scrap into the hoppers. The interlock mechanism is desirable kept as simple as possible to prevent breakdown, and is also not easily by-passed by the operator.

SUMMARY OF THE INVENTION

A storage and transfer hopper is provided, having an elongated hollow body and spaced interlocked outer and inner door proximate the charging end of the hopper. The outer and inner doors are connected to rotatable generally parallel shafts, each of the shafts has alignable engagement means mounted thereon. A movable locking arm is movably mounted between the shaft engagement means, and is normally biased to engage the inner door shaft engagement means to prevent rotation of the inner door shaft and opening of the inner door while the outer door shaft is rotatable and the outer door open. The locking arm is movable to disengage the inner door shaft engagement means and to engage the other door shaft engagement means to prevent rotation of the outer door while the inner door shaft is rotatable and the inner door open.

The outer door is preferably disposed to seat closed against the charging end of the hopper in a direction transverse to the longitudinal axis of the hopper body.

The inner body is inclined at an angle with respect to the longitudinal axis of the hopper body. The outer door opens outwardly while the inner door opens inwardly.

BRIEF DESCRIPTION OF THE DRAWING

FIG. 1 is side elevational view of the hopper embodiment of the present invention mounted over a schematic representation of a scrap granulator.

FIG. 2 is an end view of the embodiment shown in FIG. 1.

FIG. 3 is an enlarged view of the interlock mechanism with guide member 50 removed.

FIG. 4 is a partial elevational view of the interlock mechanism of another embodiment.

DESCRIPTION OF THE PREFERRED EMBODIMENT

The invention can be best understood by reference to

the exemplary embodiments shown in the drawings. In FIGS. 1 and 2, the hopper 10 is mounted above a conventional scrap granulator 12. The hopper 10 comprises a generally rectangular or square cross-sectional hollow body defined by the four side walls 14. The hopper is inclined at an angle to facilitate charging and movement of the scrap. An outer door 16 is disposed at the charging end 18 of the hopper 10 generally transverse to the longitudinal axis of the hopper. The outer door 16 is connected by generally L-shaped brackets 20 to the outer door shaft 22. One end 24 of the L-shaped bracket 20 is fixed to the exterior of the outer door 16, while the other end 26 is rotatably mounted on shaft 22. The shaft 22 thus acts as the pivot line for outer door 16 when the door is swung upward by an operator lifting handle 28.

The inner door 30 is disposed within the hopper spaced from the outer door 16. The inner door 30 is pivotally connected via bracket 32 to inner door shaft 34. The inner door 30 when in the normally closed position is inclined at an acute angle of, for example, about 45 degrees, to the longitudinal axis of the hopper.

The interlocking mechanism for the doors comprises a pair of disc or disc-like engagements members 38 mounted on one end of each of the respective shafts 22, 34. The engagement members 38 are mounted to turn with the respective shafts 22, 34 on which they are mounted. The disc members 38 as shown are aligned in a common vertical plane although not limited thereto. A generally U-shaped notch or aperture 40 is provided on the perimeter of each member 38. The members 38 are mounted in place on shafts 22 and 34 so that when each of the doors are in the closed position, the notches or apertures 40 are aligned across from each other. The disc-like members 38 are dimensioned to preferably be in approximately tangential relationship with their perimeters being slightly spaced apart. A pivotally moveable locking arm or lever 42 is pivotally connected at point 44 to the hopper wall and extends outward generally transverse to the plane in which the disc members 38 are disposed. The locking arm or lever 42 passes through the aligned aperture 40, and is dimensioned to fit within a single aperture to thereby lock or prevent rotation of the shaft to which the particular aperture disc is connected. The lever 42 is preferably biased downward by the force of gravity into engagement with the inner door shaft disc.

As the outer door is opened the disc mounted on the outer door shaft rotates and the aperture therein is no longer aligned with the inner door shaft disc aperture, and the lever is locked in position because the perimeter of the outer door shaft disc closely spaced therefrom. Only when the outer door is closed are the apertures again aligned to permit the lever 42 to be raised upward into the aperture in the outer door shaft disc to lock the outer door closed and the inner door is free to open. An inner door opening lever 48 connected to shaft 34 is swingable downwardly to inwardly open the inner door.

A locking arm guide member 50 preferably extends between shafts 22 and 34 abutting the disc members 38. The respective shafts are free to rotate within the opposite ends of guide member 50.

A centralized elongated aperture 52 is provided in guide member 50, with locking arm or lever 42 passing through the aperture 52. The aperture 52 is elongated

to permit pivotal movement of the locking arms 42 from engagement with either the inner or outer door disc apertures 40.

The hopper walls 14 each have a soundproofing material layer 54 on the exterior, as does the outer door. A resilient gasket 56 is disposed on the interior perimeter of the outer door to seat against the charging end of the hopper to also serve as a vibration and sound dampening means. The outer door is preferably slightly larger than the hopper cross-section and has an outer lip portion 58 which extends around the hopper charging end, as an effective closure and sound dampening measure. The locking mechanism has been described as notched disc or disc-like members with a locking arm, and it is apparent that semicircular members or other such equivalent members can be used as well.

The inclined inner door reduces the degree of tolerance required to achieve a close sealed fit of this door. This provides a superior soundproof seal and prevents flyback of particles or wedging of same between the edge of the inner door and the hopper wall.

The hopper is charged or loaded with scrap by opening the outer door and depositing the scrap onto the inner door in the space between the doors.

For very large hoppers the outer and inner doors may be spaced a substantial distance apart and thus the shafts to which they are connected are so spaced apart. Rather than have very large disc-like engagement means in tangential relationship an alternate embodiment is shown in FIG. 4 with the other structural elements being the same as described above.

The outer door shaft 60 and inner door shaft 62 are spaced a considerable distance apart. Again disc members 64, 65 are mounted on the respective shafts 60, 62, and notches or apertures 66 are provided in perimeter edge of each disc 64, and 65. The doors are connected to the shafts so that when each door is closed the notches or apertures are aligned although spaced apart. A slidably movable engaging arm 68 is aligned with the notches or apertures and is movable from a biased normal position with lower end 70 of arm 68 engaged within notch 66 of the inner door disc 65. A pivotally movable lever 72 is pivotal about point 74 and is connected at intermediate point 76 to arm 68 to raise or lower arm 68. The spring means 78 extends downward from the lever 72 to a fixed point to bias the lever 72 and arm 68 in engagement with the inner door disc notch. A stationary mounted engaging arm guide member 80 is disposed between the outer and inner door discs, and guides arm 68 as it is moved upward and downward. The pivoting upward of lever 72 raises engaging arm 68 into engagement with the aligned notch 66 of outer door disc 64 when the outer door is closed. The interlocking mechanism thus works essentially the same way as for the other embodiment.

The double-door hopper of the present invention provides a simple and safe mechanical interlock between the doors. This provision minimizes transmission of sound through the hopper and also prevents material being ejected from the hopper.

I claim:

1. A storage and transfer hopper comprising an elongated hollow body including a charging end and a dis-

charging end, an outer door at the charging end, and an interlocked inner door spaced therefrom within the hollow body, wherein the outer and inner doors are connected to rotatable generally parallel shafts, each of said shafts having alignable engagement means mounted thereon, a movable locking arm engagable with the inner door shaft engagement means to prevent rotation of the inner door and door shaft while the outer door shaft is rotatable or open, which locking arm is movable from engagement with the inner door shaft engagement means to engagement with the outer door shaft engagement means to prevent rotation of the outer door and door shaft while the inner door shaft is rotatable or open.

15 2. The apparatus specified in claim 1, wherein the respective door shaft engagement means comprise aligned planar arcuate members having alignable locking arm receiving slots therein, which arcuate members are rotatable with the shafts when the locking arm is not disposed in the respective slot.

20 3. The apparatus specified in claim 2, wherein the locking arm comprises a pivotally mounted lever disposed transverse to the planar arcuate members, with the central portion of said lever fitting within the receiving slots.

25 4. The apparatus specified in claim 2, wherein the planar arcuate members comprise discs which are disposed in approximately tangential relationship so that when the locking arm is disposed in the receiving slot of one of the discs, and the other door and shaft are rotated open the perimeter of the other disc is opposite the locking arm preventing its removal therefrom.

30 5. The apparatus specified in claim 4, wherein an elongated slotted locking arm guide member extends between said shafts in abutting relationship with said discs, with the guide member slots being aligned with the disc receiving slots and the locking arm extended through said guide member slot.

35 6. The apparatus specified in claim 1, wherein the hopper is adapted to be mounted above thermoplastic scrap granulator, with the discharge end of the hopper mating with the granulator charging aperture.

40 7. The apparatus specified in claim 1, wherein soundproofing material is disposed on the outer door and the exterior of the hopper body.

45 8. The apparatus specified in claim 1, wherein the rotatable shafts and engagement means mounted on respective shafts are widely spaced with the engagement means disposed in aligned planar relationship, each of said engagement means including a locking arm receiving notch, and the locking arm comprises an elongated bar extending between the aligned engagement means.

50 55 9. The apparatus specified in claim 8, wherein the elongated bar is connected to a pivotally mounted lever which is used to shift the bar from engagement with one engagement means to the other.

60 10. The apparatus specified in claim 1, wherein the outer door is opened outward by moving the door away from charging end, and the inner door is opened inward by moving the door in the opposite direction.
